UNITED STATES PATENT OFFICE.

SAMUEL PEARCE, OF HOLYOKE, MASSACHUSETTS, ASSIGNOR TO DRAPER COMPANY, OF HOPEDALE, MASSACHUSETTS, A CORPORATION OF MAINE.

UNWRAPPING MECHANISM FOR YARN-CHAINS.

SPECIFICATION forming part of Letters Patent No. 732,439, dated June 30, 1903

Application filed April 14, 1903. Serial No. 152,571. (No model.)

To all whom it may concern:

Be it known that I, SAMUEL PEARCE, a citizen of the United States, and a resident of Holyoke, county of Hampden, State of Massachusetts, have invented an Improvement in Unwrapping Mechanism for Yarn-Chains, of which the following description, in connection with the accompanying drawings, is a specification, like characters on the drawings representing like parts.

The advantages of wrapping or coiling an extra thread or cord around a chain of yarn-threads preparatory to the process of dyeing or bleaching are well known, and yarn-chains are very generally so prepared at the present time. After the wrapped chains have been bleached or colored and dried the thread or cord coiled around the chain must be unwrapped or removed before the chains are re-wound either onto beams for warp-yarns or onto filling bobbins or quills if the yarn is to be used for filling. Apparatus has been devised to readily and economically remove the wrapping-cord from the chain and wind it upon a suitable receiver in condition for further use, either for wrapping around another chain or for other purposes, and United States Patents Nos. 550,656 and 550,657, dated December 3, 1895, show very successful apparatus of this character. In the former patent the ratio between the linear speed of the chain and the rotary speed of the flier which unwraps the cord is varied at the will of the operator by varying the chain speed, and in the later patent such ratio is varied by changing the speed of rotation of the flier, the chain speed remaining constant.

I have shown my present invention as practically embodied in an apparatus of the latter type, though its use is not restricted thereto.

As set forth in the patents referred to the angle at which the cord leaves the chain during unwrapping must be obtuse enough to reduce to a minimum the liability of the cord to cling to the chain. This is effected mainly by the position of the point at which the cord leaves the chain, such point being governed by the relation between the linear chain speed and the rotary speed of the unwrapping means or flier. Increased linear or de-

creased rotary speed tends to lower the point, while decreased linear or increased rotary speed tends to raise it. Could these speeds be exactly proportioned to the rate at which the cord is coiled around the chain and could this rate as well as these speeds be continuously maintained, the point at which the cord leaves the chain would not vary. In practice this is not possible, and the point is constantly rising and falling, and if it rises too high the cord is broken at the guide above the machine, while if the point falls too low the cord will be broken by engagement with some part of the unwrapping means.

In the patents above mentioned means are provided whereby the operator can vary the ratio between the chain speed and the speed of the unwrapping means, so that the position of the point at which the cord leaves the chain is under the control of the operator, a reasonable variation being provided for, so that continual watching by the attendant is not absolutely necessary. A stop-motion device is also provided to stop automatically the machine when the cord breaks or slackens unduly.

My present invention has for its object the production of means for automatically controlling the ratio between the chain speed and the flier speed, so that not only can the operator attend to a greater number of unwrapping-machines, but each machine can be run more continuously than has been possible heretofore, and whether by natural or artificial light. The latter is an important point, inasmuch as with artificial light and with some colors in daylight the attendant has heretofore been obliged to assist his eyesight by feeling with his hand the cord to judge of the position of the point of departure thereof from the chain.

In the present embodiment of my invention the substantially highest practical ratio between the linear speed of the chain and the rotary speed of the unwrapping means is adopted as the normal ratio, and the machine is adjusted to run at such rate. If then the unwrapping gains unduly upon the chain speed, thereby raising the point of departure of the cord dangerously near the overhead guide, simple and effective means are brought

into action automatically to quickly decrease the speed ratio to a point below the normal rate, and the point of departure falls suddenly. Thereupon the speed ratio is gradually and automatically raised until the normal rate is restored, and the automatic means will be reset or returned to its normal inoperative condition in readiness to again act as before when occasion demands. The speed ratio is governed automatically and directly by or through the cord as it is unwrapped without requiring any attention or assistance upon the part of the attendant. By adopting a normal speed ratio as high as practical there is practically no danger of the point of departure of the cord falling too low, and the stop-motion is called into play only by breakage of the cord, which is of comparatively infrequent occurrence.

The various novel features of my invention will be described hereinafter and particularly pointed out in the following claims.

Figure 1 is a side elevation, broken out between the overhead guide and the lower part of the apparatus, of a machine for unwrapping yarn-chains embodying one form of my invention, the means for changing the speed ratio being shown in normal or inactive condition. Fig. 2 is an enlarged partial elevation and section on the irregular line 2 2, Fig. 1, looking toward the right to show more clearly the belt-shifter and the automatic means for moving it. Fig. 3 is a greatly-enlarged detail, in side elevation, of the locking device which retains in inactive condition the means for changing the speed ratio. Fig. 4 is a rear elevation thereof viewed from the right, Fig. 3. Fig. 5 is a transverse sectional view on the line 5 5, Fig. 4, looking down; and Fig. 6 is a right-hand end elevation of the mechanism shown at the upper part of Fig. 2, the belt-forks being shown.

The main frame A, the main driving-shaft B, provided in practice with fast and loose pulleys connected by a belt B^X, Fig. 1, with a suitable source of power, and rolls B³ and B⁴ (shown in dotted lines Fig. 1) may be and are substantially as in said Patent No. 550,657, the roll B³ being fast on the shaft B and roll B⁴ is mounted in suitable stands. (Herein omitted to render the drawing clearer.) Herein the shaft B is extended beyond the frame A and has secured to it a cone-pulley C, (shown in dotted lines, Fig. 2) connected by a shiftable belt C^X with and to drive a reverse cone C', fast on a worm-shaft C², mounted in bearings (not shown) on the frame. As the speed of shaft B is constant, shifting of the belt C^X to the right, Fig. 2, will decrease the speed of the shaft C², and its speed will be increased if the belt is shifted to the left. The yarn-chain is led between the rolls B³ B⁴ after the cord has been unwrapped from the chain, and the latter is drawn through the apparatus at substantially uniform speed by rotation of said rolls. As in the patent referred to, a bevel-gear c³ on shaft C² drives a smaller

bevel-gear d, having its hollow hub supported in the frame A, attached at its upper end to a flier F, the rotative speed of the latter depending on the position of the belt C^X upon the speed-cones C and C'. A worm e on shaft C² engages a worm-wheel e' on an upright shaft e², mounted in bearings e^X, said shaft having fast upon it near its lower end a sleeve e³⁰, provided at its upper and lower ends, respectively, with worms e³ and e³³, the former meshing with a worm-wheel e⁴ on a cam-shaft D, mounted on the main frame and having an attached traverse-cam D^X, all substantially as in the patent last referred to, save that the sleeve e³⁰ and lower worm e³³ are novel features. The hub of the gear d has extended loosely through it a hollow spindle g, Fig. 1, provided with a roll g⁵, which rests upon the periphery of the traverse-cam D^X, rotation of the latter vertically reciprocating the spindle and giving it a traverse motion in accordance with the shape of the cam, the spindle being guided in any suitable manner. A spool or cord-receiver S is slipped over the upper end of the traverse-spindle g, which projects slightly above the flier F, and the upper end of the cord-receiver, the latter resting on a washer w, held in place by a collar g^X, fast on the spindle, as in Patent No. 550,657.

The wrapped yarn-chain L, Fig. 1, is drawn over a guide-sheave G^X, located above and at a considerable distance from the top of the traverse-spindle, the chain entering the latter after the cord L has been unwrapped therefrom, the unwrapped chain passing out of the lower end of the spindle g and around a guide-sheave G and thence up through the rolls B³ B⁴ in the direction of the arrow 50. It will be manifest that the rotation of the flier unwraps the cord from the yarn-chain and winds it upon the cord-receiver S, the traverse motion laying the cord smoothly upon the receiver from end to end as it is wound thereupon. The flier is provided with guide-eyes f¹ and f⁵, through which the cord passes to the spool, and between said guide-eyes the cord leads through the eye f³ of the latch f², pivotally mounted on the flier and forming part of a stop-motion, which latter may be of the character shown in Patent No. 550,657. As the stop-motion is common and forms no part of my present invention, I have not illustrated it in detail herein, it being only necessary to state that if the cord breaks the latch f² is released and the stop-motion acts to stop automatically the machine. The means whereby the ratio between the linear chain speed and the rotative speed of the flier is changed automatically will not be described. A stand A⁵ is bolted to the main frame and projects outwardly therefrom between the speed-changing cones C and C', said stand having upturned parallel ears a a, which form bearings for an actuator for the belt-shifter, said actuator being shown in Fig. 2 as a quick-motion screw a^X, sleeved upon and secured to a shaft a' between the ears a. A nut a²

has a threaded opening through which the screw passes, said nut having depending sides a^3 , which embrace the edges of the stand A^5 , the nut being slideable thereon transversely 5 to the path of the belt C^X by rotation of the actuator a^X in one direction or the other. Belt-forks f^{10} are secured to the sides of the nut and extend above and below it, as shown in Figs. 1 and 2, to coöperate with the upper 10 and lower runs, respectively, of the belt. A clamping-bolt f^{11} passes through an elongated slot f^{12} in the base of the fork and into the nut to secure the fork to the nut, and, as will be seen by reference to Fig. 2, the fork can 15 be adjusted upon the nut transversely to the belt-path. The shaft a' is rotatably mounted in the ears a , and its ends extend beyond the ears, drums A^6 and A^7 being secured to such projecting ends for a purpose to be de- 20 scribed.

Referring now to the lower parts of Figs. 1 and 2, a bracket B^{10} , secured to the main frame A , has bearings b^{10} for a rotatable shaft b^X , provided at one end with a worm-gear b , in 25 mesh with the worm e^{38} on the shaft e^2 , so that the shaft b^X is continuously rotated. Between the bearings b^{10} a large gear b' is secured to shaft b^X , this gear at times meshing with and rotating a mutilated pinion b^2 on a 30 short shaft b^3 , carried by a bracket b^4 , secured to the main frame, Fig. 1. The pinion b^2 has teeth b^{20} on one-half of its circumference, as shown in full lines, Fig. 2, and when those teeth are in mesh with the gear b' the pinion 35 b^2 will be rotated positively through one-half a revolution. A radius-arm b^5 is secured to the face of the pinion by screws b^6 , the latter passing through longitudinal slots 10 in the arm, so that the latter can be adjusted to 40 vary the radial path of a stud b^7 on the longer end of the arm. A wire link b^8 is pivotally connected at one end with the stud, and at its other end it is attached to a chain, flexible wire, or other flexible member b^9 , which is carried 45 up to and wound around the drum A^7 and secured thereto. When by means to be described the drum is rotated in the direction of arrow 75, Fig. 6, the flexible member will be wound upon the drum, and through the 50 radius-arm b^5 the pinion b^2 will be turned in the direction of arrow 80, Fig. 2, into dotted-line position, thereby bringing the leading tooth of the series b^{20} into engagement with the gear b' . This gear is continuously rotating, it will be remembered, so that when it 55 thus engages the pinion-teeth it will rotate the pinion positively and slowly in the direction of arrow 80 until the radius-arm has returned to full-line position. During such 60 movement of the radius-arm the member b^9 will be unwound and the drum and actuator a^X will rotate opposite to arrow 75, Fig. 6, and thereby the nut a^2 will be moved to the left, Fig. 2, to shift the belt to the small end of cone C' .

Referring now more particularly to Figs. 1, 3, 4, and 5, an upright bar M is secured at M^X

to the ceiling of the room in which the apparatus is set up, the lower end of the bar being supported by a foot a^{10} , bolted to the extremity 70 of the bracket A^5 . A collar m , secured to the bar near its upper end, has attached to it one end of a strong spiral spring S^{10} , Figs. 1 and 3, the lower end of the spring being connected with an elongated flat metallic slide-bar m' , 75 longitudinally movable in guide-ears m^X , projecting laterally from a sleeve N , firmly secured to the bar M by a set-screw n . The lower end of the slide-bar has secured to it one end of a flexible connection m^2 , which is carried down 80 to and wound upon the drum A^6 oppositely to the winding of the connection b^9 upon the drum A^7 . A locking-notch m^3 is made in the inner edge of the slide-bar near its upper end, the lower lateral edge m^4 of the notch being 85 adapted to engage a latch p when the apparatus is running properly, the spring S^{10} at such time being stretched and holding the slide-bar in coöperative engagement with the latch or locked. The latch is shown as the 90 short arm of a flat lever having a fulcrum-pin p^X passed through and secured to it, the long arm p' of the lever being twisted at its extremity substantially at right angles to the body of the lever, as at p^2 . The ends of the 95 fulcrum-pin are preferably pointed, as shown in Figs. 3 and 4, and one end rests in a socket n' in the upper face of the lower ear n^X , while the other end of the pin enters a socket in the end of a screw n^2 , passing through the upper ear, the screw being out of alignment with the socket n' in order that the pin p^X will be out of the vertical, as clearly shown in Figs. 3 and 4. The inclination of the pin is such that the weight of the longer arm of 100 the latch-lever tends to turn the lever and bring the latch p into engagement with the slide-bar m' , and at such time if the notch m^3 is opposite the latch the latter will enter it and lock the slide-bar. 110

Referring to Fig. 1, it will be seen that when in normal position the blade p^2 extends past the side of the sleeve N toward the path of the unwrapped chain between the guidesheave G^X and the flier. By means of the set-screw n the sleeve N is adjusted vertically 115 on its support M at such a height that normally the blade p^2 will not touch the conical path traversed by the cord L' between its point of departure from the chain and the 120 flier, and at such time the belt-shifter and the parts are, as shown in Figs. 1 and 2, in the normal position when the machine is running properly. The flexible connection m^2 is wound upon the drum A^6 , the slide-bar m' is 125 locked, with the spring S^{10} extended, and the connection b^9 is unwound from the drum A^7 , the belt C^X being in position to give the highest ratio between the linear speed of the chain and the rotative speed of the flier. 130 Now if the unwrapping gains unduly upon the chain speed the point of departure of the cord from the chain will rise, and thereby the cord in whirling around will hit the blade

p^2 and turn the latch-lever on its fulcrum-pin, withdrawing the latch p from the slide-bar m' . Just as soon as the latter is thus released the spring S^{10} contracts, lifting the 5 slide-bar quickly, and through it the connection M^2 is unwound from and rotates the drum A^6 , turning shaft a' and the screw-like actuator a^x in the direction of the arrow 75, Fig. 6. Such rotation of the actuator 10 quickly slides the nut a^3 to the right, Fig. 2, shifting the belt to quickly decrease the ratio between the linear chain speed and the rotative speed of the flier, and the point of departure of the cord falls. At the same 15 time the drum A^7 winds up the connection b^9 , bringing the pinion b^2 into mesh with the gear b' , as has been described, and as the pinion is positively and slowly rotated the connection b^9 will unwind from its drum, re- 20 versing the rotation of the actuator a^x and gradually returning the belt to the normal speed position. By the reverse rotation of the actuator and drums the connection m^2 is wound upon its drum, drawing down the slide-bar m' until the latch p swings into the locking-notch m^3 , and just after this is effected 25 the toothless part of the pinion b^2 comes opposite the gear b' and rotation of the pinion stops. Thus the controlling mechanism is 30 set automatically after each operation thereof to shift the belt, and whenever the point of departure of the cord rises to an improper height the belt will be shifted to quickly decrease the speed ratio, and thereafter the re- 35 turn shifting of the belt is effected to restore the normal speed ratio gradually and automatically. By adjusting the belt-forks f^{10} on the nut the normal position of the belt can be regulated with relation to the speed- 40 cones C and C' . The blade p^2 provides a broad surface upon which the cord impinges and obviates any tendency to break the latter, and even if the controlling mechanism should not be unlocked at the first impact of 45 the cord upon the blade a second or third impact will be sufficient to effect unlocking. As the speed is reduced very quickly, the point of departure of the cord drops rapidly, and though the cord may engage the wing 50 55 50 after the latch is withdrawn no harm is done. By the time the controlling mechanism is set, as described, the conical path of the cord is entirely out of range of the blade of the latch-lever.

My invention is not restricted to the precise construction and arrangement herein shown and described, as the same may be varied or rearranged in various particulars without departing from the spirit and scope of my in- 60 vention.

Having fully described my invention, what I claim as new, and desire to secure by Letters Patent, is—

1. In apparatus for unwrapping yarn-chains, 65 a cord-receiver, means to unwrap the cord and to wind it upon the receiver, and means to vary automatically and positively the ratio

between the linear speed of the chain and the rotary speed of the unwrapping means.

2. In apparatus for unwrapping yarn-chains, 70 a cord-receiver, means to unwrap the cord and to wind it upon the receiver, and means operating automatically when the unwrapping gains unduly upon the chain speed, to decrease and thereafter to restore positively the 75 ratio between the linear speed of the chain and the rotary speed of the unwrapping means.

3. In apparatus for unwrapping yarn-chains, 80 a cord-receiver, means to unwrap the cord and to wind it upon the receiver, means operating automatically to instantly decrease the ratio between the linear speed of the chain and the rotary speed of the unwrapping means, and mechanism to thereafter restore automatic- 85 ally and gradually the normal ratio.

4. In apparatus for unwrapping yarn-chains, 90 a cord-receiver, means to unwrap the cord and to wind it upon the receiver, means actuated by the cord to decrease positively and automatically the ratio between the linear speed of the chain and the rotary speed of the un- 95 wrapping means when unwrapping gains unduly, and normally inoperative mechanism operated thereafter automatically to restore gradually the normal ratio.

5. In apparatus for unwrapping yarn-chains, 100 a cord-receiver, means to unwrap the cord and to wind it upon the receiver, means to de- 100 crease positively and automatically the ratio between the linear speed of the chain and the rotary speed of the unwrapping means, and a locking device to maintain said means in- 105 operative, the cord acting upon said device to release said automatic means when the un- 105 wrapping gains unduly.

6. In apparatus for unwrapping yarn-chains, 110 a cord - receiver through which the chain passes as unwrapped, mechanism to draw the chain therethrough, automatically-operated 110 means to decrease and thereafter to restore the ratio between the chain speed and the ro- 115 tative speed of the flier, when unwrapping gains unduly upon the chain speed, and a positively-rotated flier to wind the unwrapped 115 cord upon the receiver.

7. In apparatus for unwrapping yarn-chains, 120 a cord - receiver through which the chain passes as unwrapped, a positively-actuated flier to unwrap the cord and to wind it upon 120 the receiver, variable - speed mechanism to change the ratio between the linear speed of the chain and the rotative speed of the flier, and means to control automatically said mechanism and decrease the speed ratio when 125 the unwrapping gains unduly upon the chain speed.

8. In apparatus for unwrapping yarn-chains, 130 a cord - receiver through which the chain passes as unwrapped, mechanism to draw the chain therethrough, means to unwrap the cord from the chain and wind it upon the receiver, variable-speed mechanism to operate the chain-drawing mechanism and unwrap-

ping means at a predetermined speed ratio, and a controlling device for said variable-speed mechanism, to decrease automatically and positively the speed ratio to a definite point when the unwrapping gains unduly upon the chain speed.

9. In apparatus for unwrapping yarn-chains, a cord-receiver through which the chain passes as unwrapped, mechanism to draw the chain therethrough, means to unwrap the cord from the chain and wind it upon the receiver, mechanism, including a speed-changing device, to operate the chain drawing and unwrapping means, and controlling means for the speed-changing device, to quickly reduce the relative speed of the unwrapping means upon undue gain of said means upon the chain speed and thereafter to gradually accelerate the relative speed of the unwrapping means, such decrease and increase being effected through the speed-changing device.

10. In apparatus for unwrapping yarn-chains, a cord-receiver, mechanism to move the chain longitudinally, means to unwrap the cord and wind it upon the receiver, and mechanism independent of the unwrapping means and actuated by the cord to vary automatically the speed of such means.

11. In apparatus for unwrapping yarn-chains, a cord-receiver, mechanism to move the chain longitudinally, means to unwrap the cord and wind it upon the receiver, and mechanism independent of the unwrapping means to decrease automatically the speed thereof relative to the chain speed upon undue gain of the unwrapping thereover and to thereafter gradually restore the normal speed relation between the chain and the unwrapping means.

12. In apparatus for unwrapping yarn-chains, a cord-receiver, mechanism to move the chain longitudinally, means to unwrap the cord and wind it upon the receiver, and mechanism independent of the unwrapping means to reduce automatically and temporarily the speed thereof when the unwrapping of the cord gains unduly upon the linear speed of the chain.

13. In apparatus for unwrapping yarn-chains, a cord-receiver, mechanism to move the chain longitudinally, means to unwrap the cord and wind it upon the receiver, mechanism, including speed-changing cones and a connecting-belt, to actuate the chain-moving mechanism and the unwrapping means, and means to shift automatically the belt and decrease temporarily the speed of the unwrapping means relatively to the linear speed of the chain when the unwrapping of the cord gains unduly.

14. In apparatus for unwrapping yarn-chains, a cord-receiver, mechanism to move the chain longitudinally, means to unwrap the cord and wind it upon the receiver, mechanism, including speed-changing cones and

a connecting-belt, to actuate the chain-moving mechanism and the unwrapping means, a spring-actuated device to shift automatically the belt and decrease the speed of the unwrapping means when the unwrapping of the cord gains unduly upon the linear speed of the chain, and means to thereafter shift positively and gradually the belt and restore the speed of the unwrapping means.

15. In apparatus of the class described, means to move the chain longitudinally, a cord-receiver, means to unwrap the cord and wind it upon the receiver, actuating mechanism for both of said means, including speed-changing cones and a connecting-belt, a belt-shifter, a rotatable actuator therefor, means operative by or through the cord as it unwraps to turn the actuator to shift the belt and decrease the relative speed of the unwrapping means, and a positively-driven slow-motion device to thereafter oppositely rotate the actuator and thereby gradually shift the belt to restore the relative speed of the unwrapping means.

16. In apparatus of the class described, means to move the chain longitudinally, at a constant speed, a cord-receiver, means to unwrap the cord and to wind it upon the receiver, variable-speed mechanism to actuate said means, a guide located above and at a distance from the unwrapping mechanism to permit variation in the point of departure of the cord as unwrapped from the chain, automatically-operating means to at times act through the variable-speed mechanism and reduce quickly the speed of the unwrapping means, and a locking device to normally retain such automatic means inoperative, abnormal rise of the point of departure of the cord causing the latter to act upon the locking device and release the said automatically-operating means.

17. In apparatus of the class described, means to move the chain longitudinally, a cord-receiver, means to unwrap the cord and wind it upon the receiver, actuating mechanism for both of said means, including speed-changing cones and a connecting-belt, a belt-shifter, a spring to move it to decrease speed, a positively-actuated device to move it gradually in the opposite direction to restore the speed and also to set the spring, and a locking device, including a pivotally-mounted latch, to retain the belt-shifter in position when the spring is set, undue gain of the unwrapping means upon the linear speed of the chain causing the cord to engage and trip the latch to thereby release the belt-shifter and permit the set spring to operate.

In testimony whereof I have signed my name to this specification in the presence of two subscribing witnesses.

SAMUEL PEARCE.
